UNITED STATES PATENT OFFICE.

GEORGE GILMORE, OF SIMCOE, CANADA, ASSIGNOR OF ONE-HALF TO JOHN HAWTHORNE, OF SAME PLACE.

REVERSING-VALVE FOR ENGINES.

SPECIFICATION forming part of Letters Patent No. 632,459, dated September 5, 1899.

Application filed April 22, 1899. Serial No. 714,135. (No model.)

To all whom it may concern:

Be it known that I, GEORGE GILMORE, machinist, of the town of Simcoe, in the county of Norfolk, in the Province of Ontario, Canada, 5 have invented certain new and useful Improvements in Reversing-Valves for Steam-Engines, of which the following is a specification.

My invention relates to improvements in 10 reversing-valves for steam-engines; and the object of the invention is to provide a very rapid means to reverse the engine; and it consists, essentially, of a pair of pipes leading from the steam-inlet pipe to the valve-chest 15 and provided with three-way cocks and intermediate exhaust and a suitable lever and arms designed to operate the three-way cocks simultaneously to effect the reverse, as hereinafter more particularly explained.

20 Figure 1 is a sectional view of an engine provided with my improvements. Fig. 2 is a vertical section through one of the three-way valves at right angles to the section shown in Fig. 1.

25 In the drawings like letters and figures of reference indicate corresponding parts in each figure.

A is the cylinder, B the piston, and C the piston-rod.

30 D is the inlet-port leading from the valve-chest into the cylinder at one end, and E the port at the opposite end.

F is the valve-chest, which is comprised of a central enlargement f and end enlargements 35 f' and f'' .

G is the slide-valve, which is tubular in form and provided with end collars or enlargements g and g' .

40 G' is the valve-rod, which is connected and operated from a suitable eccentric on the crank-shaft.

H is the inlet-pipe, which is suitably connected to the branch pipes H' and H'' , one pipe 45 H' of which leads to the central enlargement f of the valve-chamber. The other pipe H'' leads to the end enlargement f' of the valve-chest.

h is a pipe connecting the chambers h' and h'' of the three-way cocks.

h^3 is the exhaust-port, leading from the central pipe h .

h^4 and h^5 are the three-way cocks, which are provided with the diametrical passage-ways 2 3 and the right-angular passage-ways 4 5, leading therefrom.

I and I' are the operating-arms of the cocks, which are connected together by a link i , which is connected by the link J to the lever K , suitably pivoted and having the usual plunger k , designed to engage with the quadrant L . It is by means of this lever that the position of the three-way cocks is reversed, so as to reverse the engine. In the position the engine is shown in the drawings the steam is coming through the pipe H into the enlargement f^2 of the valve-chamber F and by the port D to this end of the cylinder. The exhaust of course passes out through the port E and the enlargement f through the pipe H' , ports 4 and 2 and h out through the exhaust-pipe h^3 .

By throwing the lever K to the opposite end of the quadrant L the position of the cocks is reversed—that is, the port 5 of the cock h^5 is thrown into communication with the pipe H on the inner side to the valve and also into communication with the exhaust-pipe h^3 . The pipe H' is then made the inlet-pipe, and the steam passes in through it into the central portion f of the valve-chest and then through the port E , thereby reversing 80 the engine. The exhaust of course is carried through the port D and valve-chest enlargement f^2 and pipe H^2 .

Of course before the reverse and after such reverse the slide-valve derives its ordinary 85 reciprocating movement from the cam on the main shaft, so as to open and close the ports D and E for the admission and exhaust of the steam alternately, as is usual in steam-engines of this class, in order to give the reciprocating movement to the piston.

What I claim as my invention is—

The combination with the cylinder valve-chest, ports at each end of the valve-chest

communicating with each end of the cylinder and a main steam-supply pipe, of a double pipe leading from said main steam-pipe and communicating with the valve-chest, a valve-casing located in each branch pipe, a pipe connecting said valve-casings, an exhaust-pipe leading therefrom and three-way valves lo-

cated in said casings and means for simultaneously operating said valves, substantially as described.

GEO. GILMORE.
